HIGH DENSITY COMPRESS

Application filed April 8, 1929. Serial No. 353,492.

The invention relates to high density compresses. One of the objects of the invention is to provide an improved construction for supporting the levers for actuating the side platens of the high density compress. Another object is to provide an improved mechanism for operating the side platens. A further object is to provide an improved arrangement for applying the power to the mechanism so that the latter may, if desired, be efficiently and quickly reversed. With these as well as other objects in view, the invention resides in the novel features of construction as more fully hereinafter set forth.

15 In the drawings:-

Figure 1 is a side elevation with parts broken away of a high density compress embodying my invention;

Figure 2 is an end elevation thereof;

Figure 3 is a horizontal section on the line 3-3 of Figure 1;

Figure 4 is a view taken on the line 4-4 of Figure 1;

Figure 5 is a sectional view on the line 5—5 of Figure 3.

The high density compress has the base 1 which is formed of the spaced pairs of columns 2 with each pair connected at their upper ends by the cross bars 3, preferably integral therewith. 4 is the upper platen of the high density compress mounted upon the base and having the laterally extending portions 5 above the cross bars 3 and the depending portion 6 extending between these cross bars and serving as a spacer. 7 are tie rods extending transversely through the cross bars and the depending portion for securing the parts together. 8 is the lower platen below the upper platen and suitably guided by the columns 2 and adapted to be raised and lowered by means including the toggle levers 9 and the reduction gearing 10, this reduction gearing being above and mounted upon the upper platen 4.

45 11 are the side platens which are pivotally mounted at their lower ends upon the hinge members 12 rigidly secured to the columns. 2. These side platens are actuated by toggle levers comprising the upper and lower levers 50 13 and 14, respectively, pivotally connected

to each other with the upper levers pivotally connected at 15 to the swinging edges of the side platens and the lower levers pivotally mounted upon the shafts 16, which are spaced outwardly from and extend parallel to the side platens. The levers 13 and 14 are adapted to be in substantial alignment when the side platens are in closed position so that the force exerted upon these levers for closing the side platens tends to laterally separate the shafts 16. For supporting these shafts there are the tie rods 17 connected to the shafts and extending transversely of the ends of the compress and mounted in the brackets 18 upon the columns 2. There are also the tension rods 19 connected at their lower ends to the shafts 16 and at their upper ends to the upper portion of the base 1. In detail, the upper portions of these tension rods extend between the bifurcations 20 upon and preferably integral with the columns 2 and are threaded beyond the bifurcations for engagement by the nuts 21 which abut the washers 22 having rounded lower faces engaging correspondingly rounded upper faces upon the bifurcations. By adjusting the nuts upon the rods, the shafts 16 may be raised or lowered to provide for proper closing of the side platens.

The lower levers 14 are provided with the depending arms 23, the lower ends of which are pivotally connected to the outer ends of the links 24. The inner ends of these links are pivotally connected to the outer ends of the links 25 by the pins 26, which pins extend transversely through the cross heads 27 guided by the brackets 28. Specifically, the sides of these cross heads are slotted for engagement with the plates 29 upon the brackets. 30 and 31 are revoluble gears to the former of which the inner end of a link 25 is pivotally connected by the pin 32 and to the latter of which the inner end of the other link 25 is pivotally connected by the pin 33. These gears are in axial alignment and the pins 32 and 33, the plates 29 upon the brackets 28, and the pins connecting the arms 23 to the links 24 are so arranged that when the side platens 11 are in closed position the links 24 and 25 are in alignment and the

planes passing through the axes of the pins 26 and 32 and 33 pass through the axes of the gears to facilitate holding the toggle levers in operative position maintaining the 5 side platens in closed position.

For the purpose of locating the levers 13 and 14 in substantial alignment when the side platens are in closed position the mechanism for operating these toggle levers is made 10 adjustable to take care of inaccuracies either in the sizes of the parts or in their mounting and also to take care of wear. As shown, the links 24 are adjustable, each link comprising the inner part 34 and the outer part 35. 15 The part 34 has its inner end pivotally connected to the cooperating link 25, while the part 35 is in the nature of a yoke having its arms pivotally connected to the cooperating arm 23 and its base apertured for the passage 20 of the outer end of the part 34. Suitable nuts 36 are threaded upon the part 34 and abut the base of the part 35 to adjustably secure the part 34 to the part 35. With this 25 adjustable arrangement, it will be seen that the levers 13 and 14 can be made to assume substantially axial alignment when the side platens are in closed position and furthermore that this substantial alignment can be maintained irrespective of the wear or of the 30 adjustment of the shafts 16 to which the toggle levers are connected.

The revolute gears are mounted upon the shafts 37 and 38, respectively, which are journaled in the frame members 39 and 40, 35 respectively, below and rigidly secured to the hinged members 12. These revolute gear members are engaged by pinions 41 and 42, respectively, which are fixedly secured upon the shaft 43 journaled in the frame members 40 39 and 40. This shaft has fixedly secured thereto the worm gear 44, which meshes with the worm 45 upon the shaft 46. This shaft is adapted to be normally rotated in one direction by means of the electric motor 47 which 45 is adapted to be connected to the shaft by means of the belt 48 and the clutch 49. 50 is a brake drum fixed upon the shaft 46 between the worm 45 and the clutch 49 and adapted to be engaged by suitable braking mechanism. With this arrangement the motor 47 may be continuously driven and the operation of the side platens controlled by throwing the clutch in or out of operative 55 engagement. If some obstruction is presented while closing the side platens the clutch may be readily thrown out of engagement to allow the side platens to open under gravity. Also when the side platens are in 60 closed position the clutch may be thrown out of engagement while the bale is being compressed upon upward movement of the lower platen. Further, when the levers 13 and 65 14 have been moved off center after the compressing operation, the clutch may be thrown

out of engagement to allow the side platens to lower under gravity.

What we claim as our invention is:

1. In a high density compress, a side platen and means for actuating the same including 70 toggle levers connected to said side platen, a revolute member, a link connected to said toggle levers, a second link pivotally connected to said first mentioned link and revolute member, and a guide for the pivot connecting said links to each other.

2. In a high density compress, the combination with a side platen and means for actuating the same including toggle levers comprising a lever pivotally connected to 80 said side platen and a second lever having a fixed pivot, a revolute member, a link pivotally connected to said second lever, a second link pivotally connected to said first mentioned link and to said revolute member, and a guide for the pivot between said links arranged so that when the toggle levers are in extended position and the side platen is in closed position the plane extending through the axes of the pivotal connections 90 of said second link extends adjacent to the axis of said revolute member.

In testimony whereof we affix our signature.

ALFORD C. BARROWS. 95
